UNITED STATES PATENT OFFICE.

PAUL ARBON, OF TULSA, OKLAHOMA.

SWIVEL-JAR SOCKET.

1,331,892.

Specification of Letters Patent. Patented Feb. 24, 1920.

Application filed April 21, 1919. Serial No. 291,580.

To all whom it may concern:

Be it known that I, PAUL ARBON, residing at Tulsa, in the county of Tulsa and State of Oklahoma, a subject of the King of Great Britain, have invented or discovered certain new and useful Improvements in Swivel-Jar Sockets, of which improvements the following is a specification.

In drilling wells it is necessary to turn the bit so that a truly cylindrical bore may be formed. When employing rope formed of vegetable fibers, it is necessary for the driller to turn or twist the portion of the rope above the well in order to rotate the bit. When using the wire rope for lifting the tool it has been found that the weight of the tools, usually some two or three thousand pounds, will cause an untwisting of the strands of the rope and consequent rotation of the tools and that as soon as the rope is relieved of the weight of the tools, *i. e.*, when the latter strike the bottom of the well, the rope being connected to the tools by a swivel joint will retwist or return to normal condition. When the tools are again lifted there will occur the same untwisting of the rope and rotation of the tools, and when the downward movement of the tools is arrested, the rope will retwist. Experience has shown that the extent of twisting differs more or less from the untwisting and hence the bit will be angularly shifted at each stroke, and hence the turning of the rope by the driller is not always necessary.

It sometimes occurs when employing swivel jar sockets, of the type shown and described in Letters Patent No. 1,045,883 granted December 3rd, 1912, to Paul Arbon, assignee of J. E. Prosser, that the movement and especially the rotation of the swivel or jar will be prevented or greatly retarded by fine sand working in between the swivel or jar and the inner wall of the socket. The object of the invention described herein is to so space the swivel or jar from the inner wall of the socket as to avoid a clogging of the swivel and as it is desirable that the socket and swivel should be in axial alignment, it is a further object of the invention to provide the maintenance of such axial alignment between the spaced jar and socket. The invention is hereinafter more fully described and claimed.

In the accompanying drawings forming a part of this specification, Figure 1 is a sec-

tional elevation of a swivel jar socket embodying my improvements; Figs. 2 and 3 are transverse sections on planes indicated by the lines II—II and III—III, Fig. 1; 60 Figs. 4 and 5 are views similar to Fig. 1 illustrating certain modifications and Fig. 6 is a side elevation of the jar or piston shown in Fig. 5.

The improved device consists of a body 65 portion 1 having a central bore or passage 2 extending from the lower end of the body portion and an extension 3 having a bore or opening 4 of less diameter than that in the lower portion of the body. The smaller 70 bore extends down into the body and connects with the large bore. At the juncture of these bores is formed a shoulder or abutment 5 to receive the impact of the swiveling jar or piston 6. It is desirable for reasons stated in the patent referred to that the jar and socket should be in axial alinement and hence heretofore it has been the custom to make the jar with an external diameter 75 approximately equal to the diameter of the 80 larger bore. It has been found however, that as before stated, fine sand, etc., will work in between the jar and socket and prevent a free rotation or swiveling of the jar.

In order to avoid this clogging of the jar 85 or swivel by fine sand, the latter is made with an external diameter substantially smaller than the internal diameter of the larger bore and in order to maintain the jar and socket in axial alinement during operation, suitable means are employed for that purpose. As for example, in the construction shown in Fig. 1, a plurality of balls 90 7 are so arranged in a groove or raceway 8 formed in the inner wall of the socket, as 95 to project a distance less than one-half the diameter into the bore and bear against the periphery of the jar or swivel. The balls are inserted into the raceway through a radial opening which is closed after the balls 100 have been placed in position by a threaded plug 9. In addition to maintaining the axial alinement of the jar and socket, these balls will facilitate the rotation of the jar and swivel and the return of the rope to 105 normal condition when the jar or swivel is released from the weight of the socket and tools carried thereby.

In lieu of the construction shown in Fig. 1, the rotating members or bodies may be 110 carried by the jar or piston a shown in Fig. 4. When employing rollers, one or more

raceways 10 may be formed in one of the parts or members, as for example, in the swivel or jar 6 as shown in Fig. 4, the upper and lower walls of the raceway being undercut, as at 11, for the reception of the conical ends of the rollers 12. In order to permit of the placing of the rollers in the raceway, an internally threaded notch 13 is formed in the outer wall of one of the undercut end walls. This construction permits of one end of the rollers to be inserted into the groove or undercut 11 and the opposite ends moved laterally through the notch 13 into the other groove or undercut. After the rollers have been placed in the raceway, the notch is closed by a threaded plug 14.

The axial alinement of the jar or swivel with the socket may be attained by forming narrow collars 15 on the jar preferably adjacent to the ends of the latter as shown in Figs. 5 and 6. When using the latter construction, the collars may be transversely slotted or notched, as shown at 16 in Fig. 6, to permit of the escape of water, etc., from between the jar and socket during the movement of the jar.

For shipment and occasionally other purposes, it is desirable to prevent any rotation of the jar or swivel in the socket, and hence provision is made for locking the jar to the socket. Any suitable means may be employed for that purpose, such for example as that shown which consists in forming one or more openings through the socket in such position relative to the bore that a portion of the pins 16 when passed through these openings will project into a groove or grooves formed on the surface of the jars, as clearly shown in Figs. 1 to 4 inclusive. In the construction shown, these locking pins are held in position by forming threads on enlargements at the ends of the pins, said threaded portions screwing into the threaded ends of the holes formed in the socket.

45 I claim herein as my invention:

1. A swivel jar socket having in combination a body portion having an axial bore and provided with means for engaging drilling tools, a shoulder or abutment within said bore, a jar or piston adapted to be connected

to a rope and arranged in the bore in the body portion and having a diameter substantially less than the diameter of the bore, and means interposed between the jar and the wall of the bore for maintaining the jar 55 in axial alinement with the body portion.

2. A swivel jar socket having in combination a body portion having an axial bore and provided with means for engaging the drilling tools, a shoulder or abutment extending into the bore, a jar or piston adapted to be connected to a rope arranged in the bore in the body portion and having a diameter substantially less than the diameter of the bore and a plurality of rotating bodies 65 carried by one of said parts or elements and bearing against the other part or element to maintain the jar and body portion in axial alinement.

3. A swivel jar socket having in combination a body portion having an axial bore and provided with means for engaging the drilling tools, a shoulder or abutment extending into the bore, a jar or piston adapted to be connected to a rope arranged in the 75 bore in the body portion and having a diameter substantially less than the diameter of the bore, and a plurality of rotating bodies carried by the jar or piston and adapted to bear against the inner wall of 80 the body portion.

4. A swivel jar socket having in combination a body portion provided with means integral therewith for engaging drilling tools and having an axial bore 85 or opening, a shoulder or abutment extending into the bore, a jar or piston having a diameter substantially less than the diameter of the bore and arranged within the bore and adapted to be rotated 90 and reciprocated therein and to be connected to a rope, means interposed between the jar and the wall of the bore in which the jar operates for maintaining the jar in axial alinement with the body portion and means for 95 locking the jar as against movement in the socket.

In testimony whereof, I have hereunto set my hand.

PAUL ARBON.
